CLARENCE E. BEACH, OF BINGHAMTON, NEW YORK, ASSIGNOR TO GEORGE C. KNAPP,
OF NEW YORK, N. Y.

SIGNALING SYSTEM.

1,078,985.

Specification of Letters Patent. Patented Nov. 18, 1913.

Application filed May 6, 1912, Serial No. 695,345. Renewed July 21, 1913. Serial No. 780,368.

To all whom it may concern:

Be it known that I, CLARENCE E. BEACH, of Binghamton, in the county of Broome and State of New York, have invented certain new and useful Improvements in Signaling Systems, of which the following is a specification.

My invention relates to signaling systems and particularly to alarm systems for protecting localized territory and for protecting buildings, such, for example, as factory buildings and factory premises. Systems of this kind are designed, primarily, for sending alarm signals to a local fire brigade and for warning the occupants of a building or premises to escape. Such systems are, however, modified so that testing or drill signals can be sent thereover to selectively control the various alarm devices. Usually, signal controlling mechanism is provided at each of a number of stations, together with a local alarm device and at some central point general alarm mechanism is installed, the local alarm devices serving to warn the occupants at various parts of the building or premises and the general alarm devices serving to notify the fire brigade and to direct them to the calling station. At each station switch mechanisms are also provided whereby the circuit conditions may be adjusted for selection of desired alarm devices. In the particular system which my invention covers, adjustment can be made to cause sounding of all the alarm mechanisms both local and general; to cause any one or all of the local alarm devices to be responsive and the general alarm mechanism to be silenced; or to cause response of only the general alarm mechanism and silencing of all the local alarm devices. It is, however, very important that actual fire alarms should at all times take precedence over testing or drilling alarms, so that the fire brigade will immediately be notified as soon as an alarm of fire is sent from any station, even though some other station is at the same time using the system for testing or drill purposes.

Among the important objects of my invention are, therefore, to provide a simplified system for an alarm of fire to cause sounding of all the local alarm devices and the general or fire brigade alarm devices; to provide a system which can be adjusted for control or testing purposes to select

either one or all of the local alarm devices and to exclude the general alarm mechanism; to provide a system which can be adjusted for testing or drill purposes to cause response only of the general alarm devices and to silence all of the local alarm devices; to provide such controlling mechanism and arrangement in the system that whenever a fire alarm is sent in from any station while drill signals are being sent from any other station, the fire alarm signals will not be interfered with and the fire brigade will be accurately directed to the station from which the fire alarm signals are being sent; to provide such arrangement that whenever an alarm of fire is being sent from any station even though a selective drill signal is being sent from any other station, all the local alarm devices will give warning to the occupants of the building or premises; and in general to provide a system simple in mechanism and simple in circuit arrangement and control, which is especially adapted for local protection to accurately and efficiently call and direct the fire brigade and at the same time give ample warning to the occupants throughout the building or premises to be protected.

Signaling systems for carrying out the general features of the system forming the subject of my present application, namely, to assure response at all times of the general alarm mechanism and to insure sounding at all times of all the local alarm devices, have been heretofore proposed. In such systems, however, the signaling mechanism at each station was in the form of a non-interference successive fire alarm box in which two sets of springs, one for controlling the general alarm mechanism circuit and the other for controlling the local alarm circuits, both form part of the non-interference mechanism of the box, from which it results that the succession feature of each box comes into play when such box is pulled for a fire alarm at a time when another box is set for selectively drilling the general or brigade alarm mechanism. The improvement of my present application is, however, particularly designed for utilizing non-successive signaling boxes at the various stations, as, for example, those known in the art as sector boxes, which are wound during the operation of pulling and which are capable of running for a limited number

- of rounds only after such pulling. As in the previous systems referred to, two sets of circuit controlling contact mechanism are provided, one for controlling the general 5 alarm mechanism circuit and the other for controlling the local alarm device circuit, but only the general alarm mechanism circuit controlling contacts have non-interference control so that when one station has 10 been pulled for selective drill of the general alarm mechanism and another station is pulled for fire alarm, the response of the general alarm mechanism to the drilling station will not be interfered with, but the 15 fire alarm signals will be accurately sent from the fire alarm calling station to all the local alarm devices, so that the fire brigade can be directed accurately and so that all of the occupants will be warned.
- 20 The arrangement and operation of my improved system herein can be clearly understood by reference to the accompanying sheet of drawings on which is illustrated a system adapted to carry out the various features 25 referred to.
- At each of the various stations A B C, etc., of the building or premises to be covered, a local alarm device *g* is installed and at some central point general alarm or 30 gage calling mechanism *G* and current sources *S* and *S'* are installed. At each of the stations signal box mechanism is installed having preferably sector driving mechanism, the driving train for the signal 35 wheel being wound each time the box is pulled and when released being adapted to run to give the signal wheel a certain number of rounds and then to stop. As indicated, a pull lever *a* is connected with a sector 40 gear *b* and a spring *c* is provided to be wound when the sector is swung downwardly and to restore the sector when the pull lever is released. A suitable driving train with 45 interposed ratchet mechanism connects between the sector gear and the signal wheel *d*, and transmits movement to the signal wheel only during return movement of the sector cam, this arrangement being so well known in the art that it is decided not to 50 show it. Associated with the signal wheel *d* are two signaling levers *e* and *f* both pivoted at *h* and having the points *i* and *j*, respectively, for engaging the signal wheel *d* to cooperate with the teeth and notches thereof. 55 Lever *e* has the stud *k* co-operating with contact springs *l* and *m* and lever *f* has a stud *n* for co-operating with contact springs *o* and *p*. A non-interference electro-magnet *E* has an armature structure *q* pivoted at *r* and having 60 its lower end *s* extending into the path of the pin *t* on the sector gear *b* so that when this sector gear is in normal condition, the armature will be held in attracted position and when the sector gear is started down- 65 wardly upon winding of the spring the ar-

mature will be released to be free to retract, a spring *u* tending to move the armature to retracted position. The armature lever carries below its pivot point a pin *v* for co-operating with the extended end of the signaling lever *e* to move into position below this lever when this lever is raised and the armature structure retracted, or to be in front of the pin *v* when the lever is down. In other words, the pin *v* and lever *e* co-operate during the running of the box so that the armature structure is free to retract during closures of springs *l* and *m* by the lever *e*, but is locked in attracted position by the lever *e* when the lever engages in notches of the signal wheel and the contact springs *l* and *m* are open, this being a well known non-interference arrangement in signaling boxes to prevent the signaling operation of one box from being interfered with by any box on the same line. The lever *f* has, however, no non-interference association with the armature structure and is at all times free to cause opening and closure of the springs *o* and *p* during operation of the signal wheel. As 85 shown, each box must also undergo a test period after being pulled and must run for a time longer than the longest closure in any signal before the circuits controlled by the springs *l*, *m* and *o*, *p* can be broken for the 90 first time. The springs *l* and *m* at the various stations control the circuits for the general alarm devices *G* and the springs *o* and *p* at the various stations control the circuits for the local alarm devices *g*. 100

At each of the stations suitable switch mechanism is provided for adjusting the circuit conditions for selecting the various alarm devices for response. As shown, at each station two switch arms 5 and 6 are 105 provided and connected together for simultaneous operation by a bar 7. Switch arm 5 is adapted for connection with contacts 1, 2, 3, and 4 and switch arm 6 is adapted for connection with contacts 1', 2', 3' and 4'. A 110 conductor 8 connects the switch arm 5 at station A with one terminal of battery *S* and the conductor 9 connects the other terminal of this battery with one terminal of the local alarm device *g* at the last station, 115 in this case, station C. At each station the switch arm 5 connects through conductor 10 with the signaling spring *l*, the associated spring *m* connecting with one terminal of the associated electro-magnet *E*, the other terminal of each electro-magnet connecting through conductor 11 with the switch arm 5 of the next station, until the last station is reached where the conductor 12 connects the electro-magnet with one terminal of the battery *S'*, the other terminal of this battery connecting through conductor 13 and the general alarm mechanisms *G* with the conductor 8. At station A the switch arms 5 and 6 are connected together through con- 120 125 130

ductor 14 and are connected by conductor 15 with signaling spring *o*, the associated spring *p* connecting through conductor 16 with the conductor 17 which connects one terminal of the local alarm device *g* with contact 4' at station A. The other terminal of each local alarm device connects through a conductor 18 with a conductor 19 which connects the 3' contact of the one station with the switch 10 arm 6 of the next station, a resistance *x* being interposed between the contact 3' and the connection of conductor 18 with conductor 19. At each station also the contacts 2 and 3 both connect with conductor 20 leading to 15 spring *m*.

The operation of the system can now be clearly understood. When the switch arms at the various stations are in engagement with the contacts 1 and 1', respectively, the 20 system is in normal condition for fire alarm purposes and the pulling of any box will result in response of all the local alarm devices and also the general alarm devices, so that the fire brigade is called to the signaling station and all the occupants of the building or premises are duly warned by the sounding of all the local alarm devices. During such normal condition, we have the following closed circuit through the general 25 alarm devices:—from battery S' through the general alarm devices G, conductors 8 and 10, signaling springs *l* and *m* and the electro-magnet E at station A, conductor 11 to station B, thence through conductor 10, 30 springs *l* and *m* and electro-magnet E at station B, thence through conductor 10, springs *l* and *m* and electro-magnet at station C; then through conductor 12 back to battery S'. This general alarm circuit is 35 therefore controlled by the opening and closure of the springs *l* and *m* at any station at which the box mechanism is pulled. During such normal conditions of the system we also have the following closed circuit 40 through the local alarm devices *g*:—from battery S through conductors 8, 14 and 15 and springs *o* and *p* at station A and through conductor 16 and local alarm device *g* at said station; thence through conductors 18 and 19 to station B and through 45 springs *o* and *p* and the local alarm device at said station, thence through the springs *o* and *p* and local alarm device at station C and then through conductor 9 back to battery S. This local alarm device circuit will 50 therefore be controlled by the springs *o* and *p* at any station at which the box mechanism is pulled.

To illustrate the operation of the system 55 under normal conditions, suppose that at any of the stations, for example, station A, the box mechanism is pulled for an alarm of fire, and that no other stations are operating at this time. The signal wheel at station A 60 will open and close the springs *l*, *m* and

o, *p*, in accordance with the box signal, and the box signal will be sounded on the general alarm device through the circuit before traced and will be sounded by all the local alarm devices through the circuit before 70 traced. The fire brigade will therefore be called to station A and the local alarm devices at all the stations will give warning to all the occupants of the building or premises. If, after the box at station A has been 75 pulled, the box at another station as, for example, station B, is pulled, station A will still retain full control of the general alarm mechanism, and such control cannot be interfered with by the operation of the box 80 at station B for the reason that when the box at station B is pulled, the test period must first be gone through and during this test period the general alarm mechanism circuit will be opened and the retracting armature at station B will lock the contact lever *e* at said station in raised position to keep contacts *l* and *m* closed. At station A, however, the armature will be held in attracted position by the lever *e* when this 85 lever is in its lower position to open the circuit at its springs *l* and *m*. The armature at station B upon retracting will be out of attractive range of its electro-magnet so that the signaling lever *e* will be locked in its 90 upper position and springs *l* and *m* will be held closed until the sector gear *b* returns to its normal position and the pin *t* on said gear engages end *s* of the armature structure to restore it to attracted position to thereby release the signaling lever *e*, and this will only be after the box at station A 95 has fully concluded its operation and transmitted its full signal to the general alarm mechanism. However, as the signaling levers *f* are not under non-interference control, the springs *o* and *p* at station B will be opened and closed so that the local alarm circuit will be opened and closed by the 100 springs as well as by these corresponding 105 springs at station A. All the local alarms will therefore respond but may not give station A signal. However, as the main purpose of these local alarm devices is to warn the occupants, such interference of signals 110 on these local devices will not be of any consequence. The main purpose has been accomplished, namely to call the fire brigade to station A and to sound all the local alarm devices. Of course, as soon as the general 115 alarm devices stop sounding the signal of station A, the box at station B can again be pulled, if desired, and its alarm will then be given by the general alarm devices and will be given accurately by all of the local alarm 120 devices. Thus when the system is in normal condition and one box is pulled before another, the box first pulled will control the general alarm devices and both boxes when 125 running together will together sound the 130

local alarm devices and, as soon as the box first pulled comes to rest, the local devices will be controlled solely by the box last pulled and will sound the box signal on the local alarm devices. If, when the system is in normal condition two boxes are pulled so as to together break the circuits for the first time, the box first breaking the lines while the other box is closing the lines will maintain control and the contact springs *l* and *m* at the other box will then be locked in closed position by their retracted controlling armature, but the springs *o* and *p* at both boxes will together control the circuit for the local alarm devices and those local alarm devices will sound, although they may not give the signal of either box. This non-interference arrangement for the simultaneous starting of boxes, is well understood in the art.

Coming now to the abnormal condition of the system, as, when the system is to be used for selective testing or drilling, suppose that at one of the boxes—say at station A—the switch arms are moved into the second position into engagement with contacts 2 and 2', respectively. For such setting of the switch mechanisms, pulling of the box will result in silencing of the general alarm devices and response of all the local alarm devices to the signal of the box at station A. The silencing of the general alarm devices is controlled by a circuit closed therethrough when the switch mechanisms are moved to second position, such setting of the switch mechanism causing the closure of a short circuit path about contact springs *l* and *m* at station A by the conductor 20, the holding circuit being then, as follows:—from battery *S'* through the general alarm devices *G*, conductor 8, switch arm 5 and contact 2 at station A, through short-circuiting conductor 20, through the electro-magnet *E* at station A, then through conductor 11 to station B and through the springs *l* and *m* and electro-magnet *E* at said station, thence through the springs *l* and *m* and electro-magnet at station C, and then through conductor 12 back to battery *S'*. The springs *l* and *m* at station A, although opening and closing during operation of the signal wheel, are ineffective and the general alarm devices are silenced, but the springs *o* and *p* will control the local alarm circuit and all the local alarm devices *g* will sound the signal of the box at station A, the local alarm devices being all included serially in circuit with the battery *S*. If, while the box at station A is operating to selectively sound the local alarm devices, the box at station B, for example, is pulled for an alarm of fire, this box at station B will immediately assume control of the general alarm device mechanism circuit. This is obvious for the reason that the springs

l and *m* at station A, which normally by opening the general alarm circuit would prevent the box at station B from taking control of this circuit, are short-circuited and thus unable to open the circuit so that the electro-magnet at station B will remain energized and its associated contacts *l* and *m* will remain operative to control the general alarm circuit, and the signal of box B will be sounded by the general alarm mechanism and the fire brigade will be directed to station B. The springs *o* and *p* at both boxes A and B will, however, be operating at the same time for a period, but the local alarm devices, although perhaps not correctly sounding the signal of either of the pulled boxes, will, nevertheless, sound and warn the occupants. The fire alarm signal from station B thus takes precedence and the general alarm devices will sound the station B signals and the signals cannot in any wise be interfered with by the box running at station A.

If the switch mechanism at any station as, for example, station A, is moved to third position and the box pulled, only the local alarm at station A will respond and all the other local alarm devices and the general alarm mechanism will be silent. Such silencing of the general alarm devices results by the short-circuiting by conductor 20 at station A of the signaling springs *l* and *m*, and the silencing of the local alarm devices outside of station A is caused by the closure of a holding circuit, as follows:—from battery *S* through conductor 8, conductor 14 and switch arm 6 and contact 3' at station A, the resistance *x* at station A, conductor 19 to station B, conductor 15 and springs *o* and *p* and the local alarm device at said station, then through conductors 18 and 19 to station C and through the springs *o* and *p* and local alarm device at said station and then back through conductor 9 to battery *S*. At station A the resistance *x* is bridged by a circuit including switch arm 6, conductor 15, springs *o* and *p*, and the local alarm devices *g*. Now, as the box at station A runs, the general alarm mechanism circuit remains closed, as the springs *l* and *m* are short-circuited, and the circuit including the local alarm devices at stations B, C, etc., will remain closed and these local alarm devices will remain silent. At station A, however, the current shunted from this closed circuit about resistance *r* will be interrupted as the springs *o* and *p* are opened and the local alarm device at station A will thereupon sound the signal of the station box. If, now, while the box at station A is operating in the third position, the box at another station, say station B, is pulled to sound an alarm of fire, this box will take immediate control of the general alarm mechanism circuit and such control

cannot be interfered with by the operating mechanism at station A, and the general alarm mechanism will sound the signal of the box at station B and will direct the fire brigade to this station. The springs *o* and *p* at both stations A and B will, however, together control the local alarm device circuit for a period and though these local alarm devices may not clearly give either 10 of the box A or B signals, they will, nevertheless, all sound to warn the occupants. If, while any box at any station has the switch mechanism set to the second or third position, but the box is not pulled, and then the 15 box at another station is pulled, the box at this other station will of course control both the general and local alarm device circuits and the box signals will be given accurately on all the devices.

20 If it is desired to control only the fire brigade from any station, the switch mechanism at this station is set to the fourth position into engagement with contacts 4 and 4'. If this is done at station A for example, the contact springs *l* and *m* at this station will be free to control the general alarm circuit and to prevent interference with the general alarm signaling by any other box. However, at station A, the 25 switch arm 6, together with conductors 15, 16 and 17 and contact 4', will form a short-circuit path about the springs *o* and *p* so that these springs lose control of the local alarm device circuit and this circuit remains closed during operation of the box at station A. If, while the box at station A is operating under the fourth position setting, the box at another station, say station B, is pulled for an alarm of fire, this 30 box cannot take control of the general alarm mechanism circuit for the reason that this circuit is still controlled by the springs *l* and *m* at station A, so that the non-interference mechanism is effective and the signaling lever *e* at station B will be locked to hold its springs *l* and *m* closed as soon as the circuit is broken at station A while the lever *e* at station B is operating on the test tooth of the signal wheel. However, the 35 springs *o* and *p* at station A being short-circuited and inoperative, the springs *o* and *p* at station B will assume control of the local alarm device circuit, and the station B signal will be sounded on all of these local alarm devices. When the box at station A was set in operation to send its signal through the general alarm mechanism circuit the fire brigade of course responded and went to station A. The operator at station A knows, of course, that for a brigade drill the local alarm devices should not sound, and therefore immediately upon sounding of the local alarm devices when the box at station B is pulled, the operator 45 at station A will know that an alarm of fire

has been sent in from station B and he will immediately direct the fire brigade to said station. Thus the fire brigade will be accurately directed to the station sending in the fire alarm and all the local alarm devices will sound and will warn the occupants, and there is no interference in signals. If the box at station B had been pulled for fire alarm after the switch mechanism at station A had been set to the fourth 50 position, but before the box at station A had been pulled, then of course the box at station B would take control of the general alarm mechanism circuit, and the box B signal would be sounded on the general alarm mechanisms and on all of the local alarm devices, and the box A would be entirely locked out if pulled after pulling of the box at station B. Where the springs *o* and *p* at two boxes are operating at the same 55 time to open and close the local alarm device circuit, the local alarm devices will respond to substantially all of the openings in the circuit by each set of springs if a closed signal wheel is used, and the occupants will thus be thoroughly aroused.

I thus provide a very simple system in which non-successive boxes can be effectively utilized and which system, though designed primarily for fire alarm purposes, 60 can be adjusted for testing and drill purposes and in which system the arrangement is such that an alarm of fire cannot be lost, nor can there be failure of all the local alarm devices to sound during a fire 65 alarm, so that the fire brigade will, under all conditions, be accurately directed to the fire alarm sending station and all the occupants will be thoroughly alarmed; furthermore, such general alarm signals can 70 never be interfered with by other stations which are set for drilling or operating conditions or which are operating or set in operation after thus being set.

I do not, of course, desire to be limited to the precise construction and operation which I have shown and described, as changes and modifications are possible which would still come within the scope of the invention, and I therefore claim the following:

1. In a signaling system, the combination of a general alarm circuit and a local alarm circuit, a plurality of stations, circuit controllers at each station in the general alarm and local alarm circuits respectively, a signal formulating mechanism at each station for operating both circuit controllers, and non-interference mechanism at each station for preventing interference between signals when the signal formulating mechanisms at a number of stations are operating at the same time, the general alarm circuit controllers only being subject to the non-interference control of said mechanism, as set forth.
2. In a fire alarm system, the combination

of a plurality of non-interference fire alarm signal boxes connected by two electric circuits with a central station, the signaling mechanism of each of said boxes including two circuit controllers, one in each circuit, means for operating the same to send a box number signal over each circuit, an alarm at the central station arranged in one of said circuits and subject to control of the non-interference mechanism of each signal box, an alarm associated with each box arranged in the other of said circuits and independent of the control of said non-interference mechanism, and means at each local station for variably controlling the responsive action of the said alarm.

3. In a signaling system, the combination of a plurality of stations, each having signal formulating mechanism and local alarm mechanism, general alarm mechanism, circuits for connecting said various mechanisms, switch mechanism at each station adapted to adjust the circuits to cause response of all the alarms or of the local alarms only upon actuation of the signal formulating mechanism, a non-interference electro-magnet and mechanism associated therewith at each station for preventing interference between signals when the signal formulating mechanisms at a number of stations are operating at the same time, the said non-interference mechanism being connected with and adapted to exercise control over the circuit including the general alarm mechanism only.

4. In an alarm signaling system, the combination of a plurality of stations, a fire alarm signaling box of the non-interfering non-successive type at each station, two sets of contacts and a signal wheel for actuating both sets of contacts in each signal box, a main alarm circuit including in series the non-interference mechanism and one set of contacts controlled thereby at each station, a local alarm circuit including in series an alarm device and the other set of contacts at each station, said contacts being independent of the control of the non-interference mechanism, as set forth.

5. In an alarm signaling system, the combination of a plurality of stations, a non-interfering non-successive fire alarm box at each station having two sets of circuit controlling contacts and one signal wheel for operating both, a general alarm circuit including in series the non-interference mechanisms and one set of circuit controlling contacts controlled thereby at each station, a local alarm device at each station, a local alarm circuit including in series said local alarm devices and a second set of circuit controlling contacts at each station, said contacts at each station acting independently of the non-interference mechanism at said station.

6. In a fire alarm signaling system, the combination of a plurality of stations, a general alarm circuit, a set of circuit controlling contacts at each station normally included in series in the general alarm circuit, a local alarm device at each station, a local alarm circuit including normally in series all the local alarm devices, a second set of circuit controlling contacts at each station normally included in the local alarm circuit, non-interference mechanism at each station including an electro-magnet, all of said magnets being connected in series with the general alarm circuit, said non-interference mechanism being associated with the general alarm circuit controlling contacts, means at each station for preventing non-interference control of the general alarm circuit and means at each station for preventing control of the local alarm circuit from said station.

7. In an alarm signaling system, the combination of a plurality of stations, a signal box at each station of the non-interfering non-successive type, a non-interference electro-magnet, two sets of circuit controlling contacts and a signal wheel for actuating the same in each box, a main alarm circuit including in series the non-interference magnets and one set of circuit controlling contacts of the several stations, the said contacts being under the control of the non-interference magnet at each station, a local alarm device at each station, a local alarm circuit including said local alarm devices and the other set of contacts at each station normally in series, said local alarm circuit contacts being independent of the control of the non-interference magnets, as set forth.

8. In an alarm signaling system, the combination of a plurality of stations, a fire alarm signaling box at each station of the non-interfering non-successive type, a non-interference electro-magnet, two sets of circuit controlling contacts and a signal wheel for actuating the contacts in each box, a main alarm circuit including in series the non-interference magnets and one set of circuit controlling contacts of the several stations, the said contacts being under the control of the non-interference magnets at each station, a local alarm device at each station, a local alarm circuit including said local alarm devices and the other set of contacts at each station normally in series, said local alarm circuit contacts being independent of the control of the non-interference magnets, and switch mechanism at each station for preventing the control of the main circuit contacts by the non-interference electro-magnets, as set forth.

9. In an alarm signaling system, the combination of a plurality of stations, a fire alarm signaling box of the non-interfering

- non-successive type at each station, a non-interference electro-magnet, two sets of circuit controlling contacts and a signal wheel for actuating the contacts in each box, a main alarm circuit including in series the non-interference magnets and one set of circuit controlling contacts of the several stations, the said contacts being under the control of the non-interference magnet at each station, a local alarm device at each station, a local alarm circuit including said local alarm devices and the other set of contacts at each station normally in series, said local alarm circuit contacts being independent of the control of the non-interference magnets, and means at each station for shunting the main circuit contacts to thereby prevent the non-interference control by the electro-magnet at said station of the main circuit.
10. In an alarm signaling system, the combination of a plurality of stations, a signaling box of the non-interfering non-successive type at each station, two sets of circuit controlling contacts and a signal wheel for actuating both sets of contacts in each signal box, a main alarm circuit including in series the non-interference magnet and one set of contacts controlled thereby at each station and also including general alarm mechanism and a source of current, a local alarm circuit including in series an alarm device and the other set of contacts at each station and also including a source of current, said last named contacts being independent of the control of the non-interference mechanism, means at each station for preventing non-interference control of the main alarm circuit and means at each station for preventing control of the local alarm circuit from said station.
11. In an alarm signaling system, the combination of a plurality of stations, a signaling box of the non-interfering non-successive type at each station, two sets of circuit controlling contacts and a signal wheel for actuating both sets of contacts in each signal box, a main alarm circuit including in series the non-interference magnet and one set of contacts controlled thereby at each station and also including general alarm mechanism and a source of current, a local alarm circuit including in series an alarm device and the other set of contacts at each station and also including a source of current, said last named contacts being independent of the control of the non-interference mechanism, and means at each station adapted to adjust the circuits to cause response of all the alarms or of the local alarms only upon actuation of the signal wheel.
12. In an alarm signaling system, the combination of a plurality of stations, a signaling box of the non-interfering non-successive type at each station, two sets of circuit controlling contacts and a signal wheel for actuating both sets of contacts in each signal box, a main alarm circuit including in series the non-interference magnet and one set of contacts controlled thereby at each station and also including general alarm mechanism and a source of current, a local alarm circuit including in series an alarm device and the other set of contacts at each station and also including a source of current, said last named contacts being independent of the control of the non-interference mechanism, and means at each station for variably controlling the responsive action of said alarms.
13. In an alarm signaling system, the combination of a plurality of stations, a signaling box of the non-interfering non-successive type at each station, two sets of circuit controlling contacts and a signal wheel for actuating both sets of contacts in each signal box, a main alarm circuit including in series the non-interference magnet and one set of contacts controlled thereby at each station and also including general alarm mechanism and a source of current, and a local alarm circuit including in series an alarm device and the other set of contacts at each station and also including a source of current, said last named contacts being independent of the control of the non-interference mechanism.
14. In an alarm signaling system, the combination of a plurality of stations, two sets of circuit controllers at each station, signal formulating mechanism at each station for operating both of said sets, a main alarm circuit including general alarm mechanism and a source of current and serially including one set of circuit controllers and a non-interference electro-magnet at each station, said circuit controllers being under the control of said electro-magnet, and a local alarm circuit including a source of current and serially including the other set of circuit controllers and local alarm mechanism at each station, said last named circuit controllers not being under the control of the electro-magnet.
15. In an alarm signaling system, the combination of a plurality of stations, two sets of circuit controllers at each station, signal formulating mechanism at each station for operating both of said sets, a main alarm circuit including general alarm mechanism and a source of current and serially including one set of circuit controllers and a non-interference electro-magnet at each station, said circuit controllers being under the control of said electro-magnet, a local alarm circuit including a source of current and serially including the other set of circuit controllers and local alarm mechanism at each station, said last named circuit controllers not being under the control of the electro-magnet.

trollers not being under the control of the electro-magnet, and means at each station for variably controlling the responsive action of said alarm mechanisms.

16. In an alarm signaling system, the combination of a plurality of stations, two sets of circuit controllers at each station, signal formulating mechanism at each station for operating both of said sets, a main alarm circuit including general alarm mechanism and a source of current and serially including one set of circuit controllers and a non-interference electro-magnet at each station, ~~said~~ circuit controllers being under the control of said electro-magnet, a local alarm circuit including a source of current and serially including the other set of circuit controllers and local alarm mechanism at each station, said last named circuit controllers not being under the control of the electro-magnet, and means at each station adapted to adjust the circuits to cause response of all the alarm mechanisms or of the local alarm mechanism only upon actuation of the signal formulating mechanism.

17. In an alarm signaling system, the

combination of a plurality of stations, two sets of circuit controllers at each station, signal formulating mechanism at each station for operating both of said sets, a main alarm circuit including general alarm mechanism and a source of current and serially including one set of circuit controllers and a non-interference electro-magnet at each station, ~~said~~ circuit controllers being under the control of said electro-magnet, a local alarm circuit including a source of current and serially including the other set of circuit controllers and local alarm mechanism at each station, said last named circuit controllers not being under the control of the electro-magnet, means at each station for preventing non-interference control of the main alarm circuit and means at each station for preventing control of the local alarm circuit from said station.

In witness whereof, I hereunto subscribe my name, this 30th day of April A. D. 1912.

CLARENCE E. BEACH.
